(57) **CLAIM**

The ornamental design for tooth cleaning implement as shown and described.

DESCRIPTION

The patent or application file contains at least one drawing executed in color. Copies of this patent or patent application publication with color drawing(s) will be provided by the Office upon request and payment of the necessary fee.

1. Tooth cleaning implement

2. Tooth cleaning implement

3. Tooth cleaning implement

4. Tooth cleaning implement

Figure 1.1 is a front perspective view of a tooth cleaning implement;

Figure 1.2 is a top view thereof;

Figure 1.3 is a bottom view thereof;

Figure 1.4 is a front view thereof; and

Figure 1.5 is a back view thereof;

Figure 1.6 is a left view thereof; and

Figure 1.7 is a right view thereof.

Figure 2.1 is a front perspective view of a tooth cleaning implement;

Figure 2.2 is a top view thereof;

Figure 2.3 is a bottom view thereof;

Figure 2.4 is a front view thereof; and

Figure 2.5 is a back view thereof;

Figure 2.6 is a left view thereof;

Figure 2.7 is a right view thereof; and

Figure 2.8 is a back perspective view thereof.

Figure 3.1 is a front perspective view of a tooth cleaning implement;

Figure 3.2 is a top view thereof;

Figure 3.3 is a bottom view thereof;

Figure 3.4 is a front view thereof; and

Figure 3.5 is a back view thereof;

Figure 3.6 is a left view thereof;

Figure 3.7 is a right view thereof; and

Figure 3.8 is a back perspective view thereof.

(Continued)

Figure 4.1 is a front perspective view of a tooth cleaning implement;
 Figure 4.2 is a top view thereof;
 Figure 4.3 is a bottom view thereof;
 Figure 4.4 is a front view thereof; and
 Figure 4.5 is a back view thereof;
 Figure 4.6 is a left view thereof;
 Figure 4.7 is a right view thereof; and
 Figure 4.8 is a back perspective view thereof.
